US00D747490S

(12) **United States Design Patent**
Harkin et al.

(10) **Patent No.:** US D747,490 S
(45) **Date of Patent:** ** Jan. 12, 2016

(54) **BLOOD GLUCOSE METER**

(71) Applicant: **Roche Diabetes Care, Inc.**,
Indianapolis, IN (US)

(72) Inventors: **Thomas Z. Harkin**, Bristol (GB);
Sebastian Liedtke, Heidelberg (DE);
Anthony J. Uberta, III, Indianapolis, IN
(US); **Scott A. Wooldridge**, Carmel, IN
(US)

(73) Assignee: **Roche Diabetes Care, Inc.**,
Indianapolis, IN (US)

(**) Term: **14 Years**

(21) Appl. No.: **29/510,579**

(22) Filed: **Dec. 1, 2014**

(57) **CLAIM**

The ornamental design for a blood glucose meter, as shown and described.

DESCRIPTION

FIG. 1 is a top perspective view of a blood glucose meter; FIG. 2 is a bottom perspective view of the blood glucose meter; FIG. 3 is a top view of the blood glucose meter; FIG. 4 is a bottom view of the blood glucose meter; FIG. 5 is an upper end view of the blood glucose meter; FIG. 6 is a lower end view of the blood glucose meter; FIG. 7 is a right side view of the blood glucose meter; and, FIG. 8 is a left side view of the blood glucose meter. The broken lines in the drawing views are included for the purpose of illustrating a portion of the blood glucose meter that forms no part of the claimed design.

1 Claim, 4 Drawing Sheets
